CLAIM

The ornamental design for a cosmetic design for temperature controller for heating cooling device, as shown and described.

DESCRIPTION

FIG. 1 illustrates a perspective view of a cosmetic design for temperature controller for heating cooling device;

FIG. 2 illustrates a front view of the cosmetic design for temperature controller for heating cooling device thereof;

FIG. 3 illustrates a back view of the cosmetic design for temperature controller for heating cooling device thereof;

FIG. 4 illustrates a left side view of the cosmetic design for temperature controller for heating cooling device thereof;

FIG. 5 illustrates a right side view of the cosmetic design for temperature controller for heating cooling device thereof;

FIG. 6 illustrates a top view of the cosmetic design for temperature controller for heating cooling device thereof; and,

FIG. 7 illustrates a bottom view of the cosmetic design for temperature controller for heating cooling device thereof.
